UNITED STATES PATENT OFFICE.

JOHN H. DONOHUE, OF ST. PAUL, MINNESOTA.

HINGE.

1,094,136.

Specification of Letters Patent. Patented Apr. 21, 1914.

Application filed May 1, 1913. Serial No. 764,814.

To all whom it may concern:

Be it known that I, JOHN H. DONOHUE, a citizen of the United States, residing at St. Paul, in the county of Ramsey and State 5 of Minnesota, have invented a new and useful Improvement in Hinges, of which the following is a specification.

An object of this invention is to provide a butt hinge for doors which can be adjusted to compensate for shrinkage and swelling of doors and prevent them from binding at the jamb or in the casing in which they are hung, and cause them to fit properly. It has been customary when a door 10 has swollen or shrunk so that it binds or is too loose in its casing, or is set too close to the jamb, or if the butts are not accurately located, to plane off a part of the door or the casing or to reset the hinges for the purpose of overcoming the above objections. 15 This mode of construction has been unsatisfactory and expensive and there has been no certainty that the door would then hang properly. By the use of my improvement these objections are overcome, without 20 removing the door from its hinges or marring the paint or wooden surfaces.

In the accompanying drawing forming part of this specification, Figure 1 is a side 25 elevation of my invention; Fig. 2 is a plan looking down upon the upper edge of my improved hinge; Figs. 3 and 4 are sectional views showing different positions in which the members of the hinge may be adjusted; Fig. 5 is a side elevation of the pintle; Fig. 6 is a side elevation of another form of my 35 invention; Fig. 7 is a detail in section taken upon the line A—A of Fig. 6; Fig. 8 is a side elevation of another form of my invention, and Fig. 9 is a side elevation of the pintle employed in the construction illustrated in Fig. 8.

In the drawing, A and B indicate the two leaves of a hinge of ordinary form, provided with the usual screw openings 2, through which screws may be passed for securing the leaves of the hinge to the door and the jamb or part of the casing against which the face of the door abuts when 45 closed. The leaves A and B are formed with the usual knuckles 3 and 4, through which the pintle member C is adapted to be passed, and upon which the leaves of the hinge swing. This pintle has two portions 5 and 6, the respective axes of which are arranged eccentric or offset for the purpose of

providing adjustment between the leaves of the hinge to vary the space between the face of the door and the face of the jamb in the frame containing the door, and also to vary 60 the position of the door as regards the stop on the jamb and compensate for shrinkage and expansion of the parts. The knuckles 3 and 4 have their vertical openings 7 and 8 out of axial alinement, so that by 65 turning the pintle and securing it to one of the knuckles in selected position such as by the set screw 9, the leaves of the hinge are made to swing on an axis according to the position in which the pintle is set. The 70 portion 5 of the pintle is larger in diameter than the portion 6 and the openings 7 and 8 correspond in diameter to freely admit the parts of the pintle without loss in motion. The pintle is formed with a circular 75 body 10, which is illustrated in Fig. 1, and is interposed between the knuckles 3 and 4 when the leaves are connected by the pintle. This body is provided with a series of radial openings 11 in its periphery into any 80 one of which a pin or instrument may be inserted for the purpose of turning the pintle when adjusting it into horizontally selected position to adjust the relative position of the leaves.

The upper end 5 of the pintle is connected to an end piece 12 of usual form the mode of connecting being by shrinking or otherwise fastening the end 12 in the end of the pintle. The lower knuckle 3 is provided 85 with an end piece 13, corresponding to the upper end piece, said lower end piece being shrunk or otherwise fastened in the lower end of the knuckle. This construction permits the leaf B to be disconnected from the 90 leaf A by loosening the screw 9 and releasing the pintle. For the purpose of lightening the construction and saving material the upper portion 5 of the pintle may be cut 95 away at 14.

The leaves and pintle may be variously modified within the scope of my invention without departing from the principle which I have applied, for instance, in the construction appearing in Figs. 6 and 7 which 100 illustrates one modification. In these figures the leaf B is formed with one knuckle 21 and the other leaf A with a pair of knuckles 16 and 17, between which the knuckle on leaf B is positioned longitudinally. The 105 three knuckles form a longitudinal passage of even bore. In the bore of knuckles 16

2
and 17 are secured two cores 15 having co-
axial longitudinal passages placed eccentric
to the axis of the passage in which the cores
are held. The pintle is formed with two end
5 members 18 and 19 which journal in said
cores and with an intermediate body 20.
The knuckle 21 receives the body portion 20
of the pintle while the cores 15 receive and
hold the pintle end members 18 and 19, said
10 cores being inserted in the knuckles 16 and
17. The end members 18 and 19 of the
pintle being of less diameter than the diam-
eter of member 20, the axis of the end mem-
bers 18 and 19 being eccentric to the axis
15 of the body 20 of the pintle and one of the
end members such as 19 being fastened in
horizontally selected position by means of
the set screw 22 in the same manner as in
the preferred construction, the leaves of the
20 hinge are caused to turn upon the pintle as
an axis, the eccentricity being according to
the selected position in which the pintle is
secured to the knuckle 16. The pintle as in
the preferred form is formed with an en-
25 larged circular projection 23, provided with
openings 24 in its periphery and adapted to
be interposed between the knuckles 17 and
18 thereby providing means which may be
engaged by a pin or other instrument for
30 turning the pintle and adjusting its axis
upon which the leaves are caused to turn,
when the screw 22 is loosened. The screw
22 it will be noted is threaded through the
upper core 19 and impinges against the up-
35 per member of the pintle to hold the pintle
in said position. By removing the screw 22,
the pintle is adapted to be lifted out from
engagement with the knuckles to separate
the leaves of the hinge. The outer ends of
40 the knuckles 16 and 17 are provided with
caps 25 and 26 which are threaded or other-
wise engaged to hold them in place after the
pintle has been inserted in the knuckles.

Another form of my invention is illus-
45 trated in Figs. 8 and 9 in which the member 27,
by which the pintle is turned into selected
position is formed on the upper end of the
pintle above the sockets of the hinge.

It is obvious that the principles involved
50 in this invention may be applied to various
forms and designs of hinges without depart-

ing from the spirit of my invention, and I
do not wish to be understood as confining
myself to the specific construction set forth
within the scope of the following claims. 55

In accordance with the patent statutes I
have described the principles of operation of
my invention together with the apparatus
which I now consider to represent the best
embodiment thereof but I desire to have it 60
understood that the construction shown is
only illustrative and that the invention can
be carried out by other means and applied
to uses other than those above set forth with-
in the scope of the following claims. 65

Having described my invention, what I
claim as new and desire to protect by Let-
ters Patent is:—

1. A hinge having a pair of leaf members
formed with knuckles and a pintle formed 70
with a pair of vertical members fitting into
said knuckles and with a laterally extend-
ing body adapted to be interposed between
said knuckles, having engagements in its
surface for turning said pintle, the axes of 75
said vertical members of said pintle being
eccentrically arranged to each other and
means for holding said pintle to one of said
knuckles in horizontally selected position.

2. A hinge, comprising, in combination, a 80
pair of leaves formed with knuckles, a pintle
having members fitted in said knuckles per-
mitting said leaves to swing, the axis of one
member of said pintle being eccentrically
arranged to the axis of the other whereby 85
the turning of said pintle varies the axis
on which said leaves are adapted to turn,
and means for holding one of said members
of said pintle in turned position in one of
said knuckles, said pintle being formed with 90
integral engaging means for turning it into
selected position said engaging means being
placed between said knuckles and laterally
accessible.

In testimony whereof, I have signed my 95
name to this specification, in the presence
of two subscribing witnesses.

JOHN H. DONOHUE.
